United States Patent Office

Des. 188,915
Patented Sept. 27, 1960

188,915

FLUORESCENT LIGHT FIXTURE

Edward G. Reaves, New York, N.Y.
(% Baida, 2419 Davidson Ave., Bronx 68, N.Y.)

Filed July 23, 1959, Ser. No. 56,904

Term of patent 14 years

(Cl. D48—23)

Figure 1 is a top plan view of a fluorescent light fixture, showing my new design.

Figure 2 is a side elevational view thereof.

Figure 3 is a bottom plan view thereof.

I claim:

The ornamental design for a fluorescent light fixture, as shown.
